LAYOUT TOOL

Donald E. Wright, Box 387, Elm Grove, Wis. 53122
Filed Oct. 20, 1965, Ser. No. 498,904
8 Claims. (Cl. 33—88)

This invention relates to an extensible device for producing angular relationships between surfaces and more particularly to a layout tool.

The device of the invention satisfies a need in construction and related industries for a selectively extensible and retractable device which can be resiliently and removably positioned between spaced surfaces and in predetermined angular relationships with respect to the surfaces.

One of the significant advantages afforded by the layout tool of the invention is the production in its use of substantial savings of time, manpower and money. The layout tool is effectively operable by one man. One adjustment of the selectively extensible and retractable edge of the tool will ordinarily suffice in placing a plurality of plumb layout marks in a number of locations between the same surfaces or similarly spaced surfaces.

While the layout tool of the invention is particularly useful in establishing plumb relationships between floors and ceiling and other spaced horizontal surfaces, it can also be effectively used in applications requiring the establishment of level or other predetermined angular relationships. Ordinarily, the tool is used for the placement of plumb layout marks for the installation of dry wall, various types of paneling, all types of door jambs and other tasks requiring the establishment of a plumb line between a ceiling and floor.

The layout tool of the invention generally used in construction involving ceilings of conventional height consists of a level portion with a single arm or extension frame slidably and removably secured to the level portion. Where conventional ceiling heights will be frequently exceeded in the normal use of the layout tool, a double or yoked arm or extension frame slideably and removably secured to the level portion is preferred. It has been found that the greater distance being spanned in the latter case can be more accurately plumbed where the extension frame is provided with a stiffer frame which is not easily deflected from alignment with the level portion.

Maintenance of a selected position of the extension frame on the level portion has been achieved utilizing several means. In one embodiment, an edge of the level portion is provided with an elongated magnet. When the magnetizable extension frame is adjusted with respect to the level portion, the magnet acts to maintain the selected position while the unit is in use. In another embodiment, resilient biasing means are positioned between abutting surfaces of the level portion and the extension frame and act to maintain the elements in preselected positions.

One of the ends of the level portion of the layout tool of the invention is provided with a resiliently responsive means for changing the longitudinal dimension of the level portion. This level portion dimensional adjustment provides an important advantage for the layout tool. When the unit has been positioned between two surfaces for establishing predetermined angular relationships, the end of the level portion carrying the resilient means is positioned against one of the surfaces, and the extension frame is adjusted until firm contact is established thereby with the other surface in the desired angular relation-

2

ship. The position maintenance means act at this juncture to maintain the level portion and frame extension in their adjusted relative positions. After marking the predetermined angular relationship between the surfaces, 5 the level portion can be biased against the resilient means to reduce its dimension and may then be removed from between the surfaces. The tool may be subsequently aligned between the same surfaces in a different location or surfaces spaced substantially the same distance apart by again reducing the longitudinal dimension of the level portion by biasing the resilient means against one of the surfaces and positioning the layout tool in the desired angular relationship between the surfaces.

Since a layout tool spans the distance between a floor 15 and ceiling, its length would ordinarily make the tool difficult to handle when not in use. The retractability of the extendable portion of the unit over the level portion thereof, however, makes it readily and conveniently transportable. For added versatility, the extendable portion of 20 the layout tool can be completely withdrawn from the level portion which can then be used solely as a level instrument.

Various other objects and advantages of the invention shall become more fully apparent from the following 25 drawings and description which describe the best mode presently contemplated for carrying out the invention.

FIG. 1 is a front elevation of the layout tool of the invention with some parts broken away;

FIG. 2 is a side elevation of the layout tool of FIG. 1; 30 FIG. 3 is a partial sectional view of the layout tool taken along line 3—3 of FIG. 1;

FIG. 4 is a fragmentary sectional view of the layout tool of FIG. 1 illustrating a resiliently responsive means positioned between the movable elements thereof;

FIG. 5 is a front elevation of a second embodiment 35 of the layout tool of the invention;

FIG. 6 is a side elevation of the layout tool of FIG. 5; and

FIG. 7 is a cross-sectional view of the layout tool 40 taken along line 7—7 of FIG. 5.

FIG. 1 illustrates the layout tool of the invention, which is generally designated 1. The layout tool consists of two basic elements, a level 2 and an extension frame 3. The layout tool illustrated in FIGS. 1 and 2 is shown to be positioned between a generally horizontal floor 45 and ceiling 5.

As can be seen in FIGS. 1, 2, 3 and 7, the level is formed with a frame, generally designated 6. The frame 6 is normally fabricated from a light-weight metal and, 50 in preferred practice, is fabricated as an aluminum extrusion having a generally I-shaped cross section. The I configuration of frame 6 defines vertically extending spaced parallel legs 7 and 8 which define parallel planes with respect to each other. The parallel legs are connected by a web section 9 having a generally uniform cross section throughout its length and which is positioned at right angles to the planes of legs. A number of longitudinally spaced openings 10 are provided in web section 9 of the level frame to lighten the frame and to facilitate the use and storage of the level.

A number of longitudinally spaced level and plumb 55 vial units 11, which are enclosed by protective casings 12, are mounted at longitudinally spaced intervals along the web section 9 of the level frame. The vial units 11 are secured to web section 9 at predetermined angles with respect to the planes of legs 7 and 8. As is shown in

FIG. 1, the protective casings 12 are secured to web section 9 by bolts 13. The level employed can be of the type described in the patent to H. J. Ziemann, 2,810,206, or in the U.S. patent application of Donald E. Wright, S.N. 377,881, filed June 25, 1964, for a "Level."

As can be most clearly viewed in FIGS. 3, 4 and 7, the leg 7 of the level frame includes a working surface 14 which is provided with a recess into which a magnetic material 15 is secured along substantially the entire length of the working surface of leg 7. The magnetic material 15 secured in leg 7 of the level frame and working surface 14 are precision machined to produce a unitary working surface which is parallel to working surface 16 of leg 8. The magnetic material serves to facilitate the use of the level by itself as a level instrument when working near magnetizable materials. The magnetic material, however, additionally serves an extension frame securing advantage, which will be more fully discussed below.

Referring more particularly to FIG. 1, it can be seen that the lower end of the level 2 is provided with an end plate 17 spanning the I-section at the bottom of the level and is connected thereto. Supporting blocks 18 are mounted upon end plate 17 on opposite sides of web section 9 and between parallel legs 7 and 8. Pairs of bolts 19 are inserted through vertically aligned openings provided in blocks 18 and end plate 17. Bolts 19 are reciprocably mounted in these openings and extend outwardly from the end of level 2 in a direction which is parallel to the plane of working surfaces 14 and 16. In forming the holes for bolts 19 in end plate 17 and in blocks 18, close tolerances are maintained to reduce the lateral displacement or wobble of the bolts to a minimum. Springs 20 are telescoped over the projecting ends of each of the bolts 19. Finally, the projecting bolt ends are threaded securely into a support plate 21. A felt or similar resilient pad 22 is secured to the outermost end of support plate 21 and is positioned in contact with floor 4 when the level is used as a layout tool. The pad 22 serves to prevent the marring or scratching of the floor upon which the layout tool is placed when in use.

As is shown in FIGS. 1 through 4, the extension frame 3 of the layout tool is connected to the level 2 for longitudinal sliding movement. The sectional view of FIG. 3 best illustrates the cross-sectional configuration of the elongated channel member 23 of the extension frame 3. Channel member 23 like level 2 is preferably formed from a light-weight metal such as an aluminum extrusion. The longitudinal axis of the channel member when connected to the level is parallel to the planes of working surfaces 14 and 16 of the level. A flange 24 is secured to the extended end of channel member 23 and projects therefrom in a plane normal to the axis of the channel member. To facilitate marking along the outer edge 25 of flange 24, the lower surface of flange 24 is gradually tapered at 26 towards edge 25.

The channel provided by channel member 23 is made to closely approximate the configuration defined by parallel leg 7 and working surface 14 thereof. When the channel member is telescoped in sliding engagement over the level, edge 25 of flange 24 is generally located in precise alignment with the corresponding edge of support plate 21. Therefore, after the layout tool has been aligned in plumb relationship between floor 4 and ceiling 5, utilizing the vial units 11, edge 25 and the corresponding edge of support plate 21 are aligned and marks may be made at the aligned points on the floor and the ceiling in preparation for a subsequent installation.

Since the extension frame is freely slidable along leg 7 of level frame 6, it has been found to be necessary to provide a means for maintaining the extension frame in a selected position relative to the level. To produce a means for maintaining the extension frame in a desired position with respect to the level, an elongated, thin leaf spring

27, as shown in FIG. 4, is secured at 28 to the surface 29 of channel member 23 opposite working surface 14 of leg 7. In applications utilizing a leaf spring 27, the channel is slightly enlarged to permit the sliding movement of the channel member 23 with respect to leg 7 allowing room for the interposition of the leaf spring between the opposed surfaces 14 and 29. The elongated leaf spring 27 acts to firmly bias flanges 30, as shown in FIG. 3, of channel member 23 into firm engagement with the innermost edges of leg 7 opposite working surface 14. Utilizing such a spring, an operator using the layout tool of the invention can grasp adjustment knob 31 and adjust the vertical position of the extension frame to a desired position on level 2 and leave it in that position while in use. The leaf spring 27 then acts to maintain the vertical relationship of the extension frame 3 with respect to the level 2.

It has been found that the leaf spring 27 can be omitted from a magnetizable extension frame or frame having a magnetizable portion. In this instance a channel defined by the channel member 23 can be made to very closely approximate the cross-sectional configuration of the parallel leg 7. The magnetic material 15 of the level will serve to maintain a preselected position between the extension frame 3 and the level 2 by magnetically attracting the material of the extension frame to the magnetic material 15 secured within the recess of the leg 7 of the level frame 6.

In the operation of the embodiment of the layout tool illustrated in FIGS. 1 through 4, the instrument is placed down with the pad 22 and support plate 21 of level 2 squarely on the floor. The channel member 23 and flange 24 of extension frame 3 are positioned in a somewhat retracted position with respect to the level 2. Level 2 is pushed downwardly against the bias of springs 20 a short distance, and extension frame 3 is extended vertically until contact with ceiling 5 is established. The layout tool is then aligned utilizing the plumb vial units 11 secured to the frame 6 of the level until a plumb relationship is established between the layout tool 1 and the ceiling 5 and floor 4. When the desired relationship has been established, the layout tool may be released and the bias of springs 20 between plates 17 and 21 co-operating with the leaf spring 27 or magnetic material 15 will maintain the layout tool in firm, but removable, engagement between the floor 4 and the ceiling 5. Plumb marks may then be made along any of the aligned surfaces of flange 24 and support plate 21.

To move the layout tool 1 to another position for establishing further plumb relationships, the level 2 is depressed against the bias of the springs 20 causing the flange to be spaced from the ceiling 5 and permitting the removal of the layout tool to another location. In the new location, the springs 20 are again depressed pushing over plate 17 close to support plate 21, and the depressing force on the unit is released permitting the flange 24 of the extension frame 3 to be biased in firm engagement with ceiling 5 after plumb alignment has been achieved. This procedure can be repeated continuously without necessitating the readjustment of the extension frame 3 with respect to the level 2 as long as the unit is being used in the same room or a room with ceilings and floors in similar spaced relationship.

Another embodiment of the invention is shown in FIGS. 5, 6, and 7. Since the level 2 shown in the embodiment of FIGS. 5, 6 and 7 is the same in all material respects to that shown in FIGS. 1 and 2, the same reference characters are used in the description of the level. In this embodiment, the extension frame 32 consists of a pair of channel members 33 positioned in sliding engagement with each of the parallel legs 7 and 8 of the level frame 6. The channel members 33 have configurations complementing those of the parallel legs 7 and 8 of the level frame 6. As is shown in FIG. 7, a leaf spring 34 is connected to the channel member 33 in sliding engagement with the parallel leg 7. This functions in the

same manner as leaf spring 27 of the first embodiment. A series of spaced bridging plates 35 are positioned at longitudinally spaced intervals between channel members 33 and are connected thereto. A flat top plate 36 spans the channel members 33 and is connected to them across their top portions. Top plate 36 extends between the channel members in a direction normal to the planes of working surfaces 14 and 16 of the level 2 when extension frame 32 is slidably positioned on the level.

This yoke-type extension frame construction is designed for layout tools to be used in applications wherein greater than normal ceiling heights are frequently encountered. The bridging plates 35 joining channel members 33 and acting in combination with the pair of channel members serves to impart substantial mechanical strength to the extension frame 32 when it is in its extended position. Extension frame 32 serves to greatly inhibit the development of bends or curves or the lateral displacement of the frame 32 when the layout tool is used to span a substantial distance between a floor and ceiling. The results produced by the embodiment shown in FIGS. 5, 6 and 7 is comparable to that achieved with the first embodiment, the improvement in the second embodiment lying in the greater strength and rigidity imparted to the extension frame 32 when in an extended position.

In use, one man can handily use either of the layout tools of the invention. He can readily align the tool between the surfaces being plumbed, leave the tool in the aligned free-standing position, mark the plumb lines, and move the layout tool to another position without adjustment. The need for one man to hold and another to mark is eliminated, as is the necessity for readjustment of the tool after each alignment.

Various modes of carrying out the invention are contemplated as being within the scope of the following claims which particularly point out and distinctly claim the subject matter regarded as the invention.

I claim:

1. A layout tool comprising a frame having parallel working surfaces connected by a web aligned in substantially normal relationship with the planes of the working surfaces, a level vial connected to the frame in a predetermined angular relationship with respect to the longitudinal axis of the frame, a plate secured to an end of the frame in normal relationship to the axis of the frame, a plurality of spaced studs slidably projecting through the plate in a direction parallel to the axis of the frame, the stud ends projecting from the plate being secured to a second plate, spring means disposed between the plates and biasing the plates apart, an extension frame provided with a channel complementing the frame portion defining the working surfaces thereof, the end of the frame opposite the plates being inserted into the complementing channel of the frame extension and being axially slidable with respect thereto, and means for temporarily maintaining the frame and the frame extension in a predetermined position with respect to each other whereby the layout tool may be adjusted between two surfaces in a predetermined angular relationship therewith, may be resiliently and removably biased between the surfaces and may be removed and replaced at points between the surfaces spaced from the original position without adjustment.

2. The layout tool of claim 1 wherein some of the studs are located on one side of the web and others on the other side of the web to minimize lateral movement between the first and second plates and to enhance the stability of the tool.

3. The layout tool of claim 1 wherein the spring means are telescoped over at least some of the studs between the first and second plates.

4. The layout tool of claim 1 wherein the temporary position maintaining means comprises resilient biasing means disposed between the frames.

5. The layout tool of claim 1 wherein the temporary position maintaining means comprises magnetic means on

one of the frames and magnetizable means on the other of the frames.

6. A layout tool comprising a frame having parallel working surfaces connected by a web aligned in substantially normal relationship with the planes of the working surfaces, a level vial connected to the frame in a predetermined angular relationship with respect to the longitudinal axis of the frame, a plate secured to an end of the frame in normal relationship to the axis of the frame, a plurality of spaced studs slidably projecting through the plate in a direction parallel to the axis of the frame, the stud ends projecting from the plate being secured to a second plate, spring means disposed between the plates and biasing the plates apart, an extension frame provided with a channel complementing the frame portion defining the working surfaces thereof, the extension frame being provided with a flange at an end thereof and in transverse alignment with the longitudinal axis of the extension frame, the frame being inserted into the complementing channel of the frame extension at the end opposite the flanged end being axially slidable with respect thereto, and means for temporarily maintaining the frame and the frame extension in a predetermined position with respect to each other whereby the layout tool may be adjusted between two surfaces in a predetermined angular relationship therewith, may be resiliently and removably biased between the surfaces and may be removed and replaced at points between the surfaces spaced from the original position without adjustment.

7. A layout tool comprising a frame having parallel working surfaces connected by a web aligned in substantially normal relationship with the planes of the working surfaces, a level vial connected to the frame in a predetermined angular relationship with respect to the longitudinal axis of the frame, a plate secured to an end of the frame in normal relationship to the axis of the frame, a plurality of spaced studs slidably projecting through the plate in a direction parallel to the axis of the frame, the stud ends projecting from the plate being secured to a second plate, spring means disposed between the plates and biasing the plates apart, a pair of channel members provided with channels complementing the frame portions defining the working surfaces thereof and connected together in parallel relationship by bridging means, the frame portions defining the working surfaces being inserted into the complementing channels of the channel members and being axially slidable with respect thereto, the bridging means connecting the channel members spanning the web of the frame, a plate secured in transverse relationship to the projecting ends of the channel members, and means for temporarily maintaining the frame and the channel members in a predetermined position with respect to each other whereby the layout tool may be adjusted between two surfaces in a predetermined angular relationship therewith, may be resiliently and removably biased between the surfaces and may be removed and replaced at points between the surfaces spaced from the original position without adjustment.

8. A layout tool comprising a frame having parallel working surfaces connected by a web aligned in substantially normal relationship with the planes of the working surfaces, a level vial connected to the frame in a predetermined angular relationship with respect to the longitudinal axis of the frame, a plate secured to an end of the frame in normal relationship to the axis of the frame, a stud slidably projecting through the plate in a direction generally parallel to the axis of the frame, the stud end projecting from the plate being secured to a second plate, spring means disposed between the plates and biasing the plates apart, an extension frame provided with a channel complementing the frame portion defining the working surfaces thereof, the end of the frame opposite the plates being inserted into the complementing channel of the frame extension and being axially slidable with respect thereto, and means for temporarily maintaining the frame

and the frame extension in a predetermined position with respect to each other whereby the layout tool may be adjusted between two surfaces in a predetermined angular relationship therewith, may be resiliently and removably biased between the surfaces and may be removed and replaced at points between the surfaces spaced from the original position without adjustment.
